UNITED STATES PATENT OFFICE.

PRESLEY B. JOHNSON, OF SACRAMENTO, CALIFORNIA.

LOCK.

1,200,949.

Specification of Letters Patent.

Patented Oct. 10, 1916.

Application filed March 17, 1916. Serial No. 84,830.

To all whom it may concern:

Be it known that I, PRESLEY B. JOHNSON, a citizen of the United States, residing at Sacramento, in the county of Sacramento and State of California, have invented certain new and useful Improvements in Locks; and I do hereby declare the following to be a full, clear, and exact description of the invention, such as will enable others skilled in the art to which it appertains to make and use the same.

This invention relates to new and useful improvements in a lock and one of its objects is the provision of a device of this character, which shall be simple, durable and efficient, and which may be manufactured and sold at a comparatively low cost.

Another object of this invention is to provide a casing, having a pivoted shackle and a locking disk, which will automatically lock the free end of the shackle upon inserting it within the casing.

A further object of this invention is to provide a novel means of locking the locking disk against rotation after the free end of the shackle has been inserted within the casing.

A further object of this invention is to provide means for releasing the locking means which holds the locking disk against rotation, whereby the free end of the shackle may be withdrawn from the casing and the locking disk will return to its normal position.

A still further object of this invention is to provide means for operating a series of recording dials upon unlocking of the shackle, to indicate the number of times the lock has been opened or unlocked.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a front elevation of a lock, constructed in accordance with my invention. Fig. 2 is a vertical sectional view of the same, illustrating the free end of the shackle locked within the casing, Fig. 3 is a fragmentary plan view, illustrating an op-

erating disk and a guard disk. Fig. 4 is a bottom plan view of the locking disk removed from the casing, illustrating the means of returning it to its normal position, 60 Fig. 5 is a fragmentary vertical sectional view, taken on the line 5—5 of Fig. 3, Fig. 6 is a vertical sectional view of one of the keys for unlocking the lock, Fig. 7 is a fragmentary plan view of the operating disk removed 65 from the casing, and illustrating the guard for preventing an incorrect key from rotating it, and Fig. 8 is a vertical sectional view of another key.

Referring in detail to the drawings, the 70 numeral 1 indicates a casing, consisting of a bottom wall 2, end walls 3, top walls 4, a rear wall 5 and a front wall 6. Formed on one end of the top wall 4 is a pair of ears 7, to which a shackle 8 is pivoted, having its 75 free end reduced as indicated at 9 and adapted to extend into the casing 1 through an opening 10 in the top wall 4. A lug 11 is formed on the shackle 8 adjacent the reduced end 9 and rests upon the top wall 4 to 80 limit the inward movement of the reduced end 9 into the casing 1 and also preventing a person from tampering with the interior of the lock when the shackle is in a locked position. The reduced end or extension 9 is 85 provided with an elongated slot 12 to be engaged by a locking means, which will be hereinafter more fully described, to firmly hold the extension or reduced end 9 from being withdrawn from the casing 1. 90

A locking disk 13 is journaled on the stud shaft 14 and is provided with arms 15, 16 and 17 thereon. When the reduced end 9 of the shackle 8 is inserted into the casing 1, it engages the arm 15 and causes the locking 95 disk to rotate and the arm 15 to engage a stop 18 carried by one of the end walls 3. When the arm 15 moves in the direction of the stop 18, the arm 16 passes into the slot 12 of the reduced end 9 of the shackle. A 100 tumbler 19 is pivoted to the rear wall 5 and rests upon the end of the arm 17 when the locking disk 13 is in an unlocked position, and as the locking disk is rotated in the heretofore mentioned manner, the tumbler moves 105 downwardly and engages the side of the arm 17 as illustrated in Fig. 2 and prevents the locking disk 13 from rotating in a reverse direction which is caused by the tension of a spring 20, that is embedded in a recess 21 110 upon the rear side thereof and which engages a lug 22 carried by the rear wall 5.

- Secured to the top wall 4 is a substantially L-shaped bracket 23, having a leaf spring 24 secured to one end and which is bent back upon itself and secured to the pivoted end of the tumbler 19 for causing the tumbler 19 to engage the side of the arm 17. The arm portion 25 of the L-shaped bracket 23 provides a guard to prevent a person from tampering with the tumbler 19 when the shackle 8 is in an unlocked position, and also provides a stop for preventing the locking disk 13 from rotating if the stop 18 is bent or broken in some manner, while the shackle 8 is in an unlocked position, thus preventing the lock from becoming useless. The tumbler 19 is provided with an enlarged portion 26 to provide an upwardly inclined working face 27 for a purpose which will be hereinafter more fully described.
- 20 An operating disk 28 is journaled on a stud shaft 29 carried by the rear wall 5 and is provided with a recess 30, similar to the recess 21 in the locking disk 13 to receive a spring 31, which engages a lug 32 carried by the rear wall 5. The operating disk 28 is provided with a key slot 33 and a plurality of arcuate shaped slots 34, which intersect the key slot 33. A plurality of guard pins 35 are secured to the rear wall 5 and extend into the arcuate shaped slots 34 of the operating disk 28, to prevent said disk from being rotated by an incorrect key. Secured to the operating disk 28, is an arm 36, having a rounded head 37, which engages the working face 27, to raise the tumbler 19 upwardly when the operating disk is turned by the key 38, which consists of a bit 39, having lugs 40 providing notches 41. The bit 39 of the key 38 is placed through the key-hole 43 of the front wall 6 and within the key slot 33 upon the end of the stud shaft 29 and the lugs 40 engage the portions that are indicated by the numeral 42 and by turning the key to the right, the 40 operating disk 28 is turned in a similar direction causing the arm 36 to raise the tumbler 19 and free the locking disk 13. The notches 41 in the bit 39 of the key 38 will allow the key to pass the guard pins 35. After the locking disk has been freed, the shackle 8 may be readily withdrawn from the casing 1.
- 50 A stud shaft 44 is secured to the rear wall 5 and has journaled thereon a guard disk 45, which overlies a portion of the operating disk 28. The guard disk 45 is provided with a key slot 46 and a projection 47. A plurality of guard pins 48 are secured to the front wall 6 and extend in the direction of the guard disk 45 and are arranged in vertical alinement with each other on the casing 1 and adjacent the key-hole 43, to prevent the guard disk 45 from being operated by an incorrect key. Before the operating disk 28 can be turned to

release the locking disk 13, by the key 38, it is necessary to turn the guard disk 45, so that the key slot 46 will be in registration with the key slot 33. In order to turn the guard disk 45 to accomplish the above result, a key 49, having a recess 50 to receive the end of the stud shaft 44 and a bit 51 having a plurality of teeth 52 forming recesses 53, which allow the bit 51 to pass the guard pins 48 and the teeth 51, to engage the projection 47. By turning the key 49 to the left, the guard disk 45 will be turned in the same direction to bring the key slot 46 into registration with the key slot 33. The key 49 is then turned to the right allowing the guard disk to remain stationary and is then withdrawn from the casing 1. The key 38 is then inserted within the casing 1 and through the key slot 46 of the guard disk 45 to engage the key slot 33 to turn the operating disk to the right for raising the tumbler 19 from an engagement with the arm 17 to free the locking disk 13, whereby the shackle 8 may be withdrawn from the casing 1.

90 A recording device is positioned within the casing 1 and consists of dials 54, 55, 56 and 57, which are journaled within the casing 1 and are each provided with a scale running from zero to nine. The casing 1 is provided with sight openings 58, whereby the scale of the dials 54, 55, 56 and 57 may be read from the exterior of the casing 1. Each of the dials are provided with teeth 59 and formed upon one of the teeth 100 of the dials 54, 55 and 56 is a projection 60, which is adapted to engage the teeth of the adjacent dial upon a complete revolution of the respective dial. Formed on the guard disk 45 is an extension 61 which 105 engages one of the teeth 59 on the dial 54 and upon every turn of the guard disk 45 to the left rotates the dial 54 to bring the next numeral of the scale in registration with the corresponding sight opening 58 110 in the front wall 6 of the casing 1.

115 Pivoted to the arm 36 is a lever 62, which is supported by a yoke 63 carried by the top wall 4. The free end of the lever 62 engages the teeth 59 of the dial 54 and rotates said dial 54 when the operating disk 28 is turned to the right by the key 38 to unlock the locking disk 13. Thus it will be noted that the dial 54 is turned twice upon unlocking the lock once, whereby a 120 person may determine if an unauthorized person has been tampering with the guard disk 45 or turning same and also it can be determined if the lock has been opened by an unauthorized person by keeping note 125 of the numerals showing through the sight openings 58, when the lock was last unlocked.

130 Secured to the front wall 6 of the casing 1 is a key-hole guard plate 64 which is

normally held over the key-hole 43 by a spring 65 and a guard plate 66 is adapted to close the openings 58 by the tension of a spring 67, to prevent dirt and other foreign matter from entering the casing 1.

While I have shown and described the preferred embodiment of my invention, it will be understood that minor changes in construction, combination and arrangement 10 of parts may be made without departing from the spirit and scope of the invention as claimed.

Having thus described my invention, what I claim is:

1. A lock comprising a casing, a shackle pivoted to said casing at one end thereof, the free end of said shackle reduced and inserted within the casing, the reduced free end of the shackle provided with an elongated slot therein, a locking disk journaled in said casing, three arms secured to said disk, a stop secured to said casing adjacent the locking disk for engagement with the first arm when the second arm engages the elongated slot of the reduced free end of the shackle, means for engaging the third arm to prevent reverse rotation of the locking disk, and means for releasing the locking means to allow the locking disk to rotate in a reverse direction to allow the reduced free end of the shackle to be withdrawn from the casing.

2. A lock comprising a casing, a shackle pivoted to said casing at one end thereof, a reduced extension formed on the free end of said shackle and adapted to extend into the casing, said extension provided with an elongated slot therein, a locking disk journaled in said casing, means carried by the locking disk for an engagement with the extension for rotating the locking disk when the extension is moved into the casing, means carried by the locking disk for extending through the elongated slot, an arm carried by the locking disk, a substantially L-shaped bracket secured to the casing to provide a guard for said arm, a tumbler pivoted to said casing and adapted to engage the arm to hold the locking disk against reverse rotation, and means for raising the tumbler from an engagement with the arm to allow the locking disk to rotate in a reverse rotation to free the extension of the shackle.

3. A lock comprising a casing, a shackle pivoted to said casing at one end thereof, an extension formed on said shackle and adapted to extend into the casing, said extension provided with an elongated slot therein, a spring pressed locking disk journaled in said casing, means carried by the locking disk for engaging the end of the reduced extension for rotating the locking disk when the extension is inserted within the casing, means carried by the locking

disk for engaging the elongated slot in the extension, an arm formed on the locking disk, an L-shaped bracket secured to said casing, a tumbler journaled in said casing, a leaf spring secured to one end of the 70 L-shaped bracket and bent intermediate its ends and secured to the tumbler for holding the tumbler into an engagement with said arm, and means for raising the tumbler against the tension of said spring for allowing the locking disk to rotate in a reverse direction.

4. A lock comprising a casing, a shackle pivoted to said casing at one end thereof, an extension formed on said shackle and adapted to extend into said casing, a spring pressed locking disk journaled in said casing, means carried by the locking disk for detachably securing the extension to the locking disk, a spring pressed tumbler pivotally secured to the casing for preventing reverse rotation of the spring pressed locking disk, an operating disk journaled in said casing, an arm carried by said operating disk for an engagement with the tumbler, 90 and means for rotating the operating disk to raise the tumbler to allow the locking disk to rotate in the reverse direction.

5. A lock comprising a casing, a shackle pivoted to said casing at one end thereof, an extension formed on said shackle and adapted to extend into the casing, a spring pressed locking disk journaled in said casing, means carried by the locking disk for detachably securing the extension to the locking disk, an arm secured to the locking disk, a spring pressed tumbler pivoted to said casing and adapted to engage the arm to prevent reverse rotation of the locking disk, a spring pressed operating disk journaled in said casing, an arm formed on said operating disk for an engagement with the tumbler, said operating disk provided with a key slot and a plurality of arcuate slots, a plurality of guard pins carried by the 110 casing and extending into the arcuate slots, and a key for rotating the operating disk to raise the tumbler and allow the locking disk to rotate in a reverse direction.

6. A lock comprising a casing, a shackle pivoted to said casing at one end thereof, an extension formed on said shackle and adapted to extend into the casing, a spring pressed locking disk journaled in said casing, means carried by the locking disk for detachably securing the extension to the locking disk, an arm secured to said locking disk, a spring pressed tumbler pivoted to said casing and adapted to engage the arm to hold said spring pressed locking disk 120 against reverse rotation, a spring pressed operating disk journaled in said casing, an arm secured to said operating disk and engaging the tumbler, said operating disk provided with a key slot, a guard disk journaled 125

in said casing and overlying a portion of the operating disk, said guard disk provided with a key slot adapted to be brought into registration with the key slot of the operating disk, means for rotating the guard disk and the operating disk, and a recording means operatively connected to the operating disk and to the guard disk

to record the number of times the operating disk and the guard disk are rotated. 10

In testimony whereof I affix my signature in presence of two witnesses.

PRESLEY B. JOHNSON.
